UNITED STATES PATENT OFFICE.

EGERTON RYERSON CASE, OF TORONTO, ONTARIO, CANADA.

ELECTRIC HEATING UNIT AND METHOD OF FORMING AND ASSEMBLING SAME.

Application filed December 12, 1924. Serial No. 755,489.

My invention relates to improvements in electric-heating units, and method of forming and assembling same, and while the field for my heating-unit in use is practically unlimited, I have particularly designed it for use in connection with devices used in medicating air, for the treatment of diseases or affects of the respiratory organs, such as that disclosed in my application, Serial No. 10 755,490, filed December 12th, 1924, for improvements in devices for treating air, and the principal object of my invention is to provide a fixed type of support adapted in a particular manner to receive or support 15 different windings or lengths of a single resistance-element in order to produce heating-units of different heating-capacities. Another object of my invention, in its preferred form, is to removably associate the 20 heating-unit with a support therefor, and in the following specification I shall illustrate and describe three disclosures within my invention, and what I claim as new will be set forth in the claims forming part of this 25 specification.

Fig. 1 is a plan view of my preferred form of resistance-element support showing it removably associated with a suitable support. Fig. 2 is a front elevation of said resistance-element support associated with its support which is also shown in front elevation. Fig. 3 is a vertical cross section on the line 3—3, 30 Fig. 1, showing a resistance-element in place. Fig. 4 is a plan view of an alternative form of resistance-element support. Fig. 5 is a vertical cross section on the line 5—5, Fig. 4, without the resistance-element. Figs. 6 and 35 7 are respectively front and side elevations of a still further form of resistance-element support, Fig. 7 being broken away in part to show the holder for the treating-agent.

In the drawings, like characters of reference refer to the same parts.

In the embodiments of the idea disclosed 45 in this application, only two terminal places or openings are required for the resistance-element, whether it occupy all, or only a portion of, the open floored grooves, channels, or passages, separating certain parts of my resistance-element support, and hereinafter referred to, for the sake of brevity, as passages.

It is well-known that various treating-agents require different temperatures to 55 change their state, and in some cases it is

most important that the temperature to which a treating-agent be subjected shall not go above a certain degree, as otherwise an undesirable chemical change would be effected therein. For example, a well-known 60 treating-agent in liquid form, cresolene, must be vaporized at relatively quite a low temperature so as not to impair its efficacy. On the other hand, sulphur, in powder or cake form, requires relatively a much higher 65 temperature to transform it for fumigating purposes.

With reasonable care in the use of this device, no mistake need be made in the degree of heat to which a treating or fumigating agent should be subjected.

In the form of this invention where the unit may be disassociated from its support, it will be readily understood that in case of replacement being necessary, considerable 75 saving in upkeep will be effected where only either of said elements must be replaced.

By providing a fixed type of resistance-element support with two terminal openings or places only, and having intercommunicating major and minor passages between spaced portions thereof from which may be arbitrarily selected passages to form a continuous path which will essentially intersect other possible "wiring" paths in said support, and in which it is desired to place a resistance-element and the ends of which path terminate at said terminal places or openings, I save the cost of a multiplicity of dies or moulds to produce electric-heating 85 units of different heating-capacities, or temperature ratings, and produce what I term a "universal" resistance-element support.

It is proposed to market the device herein referred to in its preferred form, with a set 95 of heating-units, each unit having a given heating-capacity, so that according to the character of the treating-agent to be transformed the heating-unit required may be associated with its support, and this with no 100 more trouble than is involved in screwing an electric light bulb or lamp into its socket.

It is self-evident that the embodiment of the idea under disclosure, in its preferred form, possesses commercial advantages of a 105 high character, and enables a unit-replacement system assuring substantially positive temperature-control to be carried out in respect of electric-heating units or hot plates apparently not heretofore attained.

While a heating-unit herein referred to is in operation, there is no dead nor idle resistance-element associated therewith.

- 5 The resistance-element herein referred to 5 may be the ordinary resistance wire uncovered, or it may be in the form of a sheathed or covered wire or other current-conducting element adapted to generate heat in association with an electric current.
- 10 While the drawings show the various embodiments of the resistance-element support as made of a block of refractory material, such as porcelain, the same may be made of metal or any other suitable material.
- 15 While the invention in question has been particularly developed for the purpose of medicating air, for the treatment of diseased respiratory organs, it may be used for various other purposes, such as fumigating or bleaching.

In my preferred form of invention, the electric-heating unit embraces a support 2 provided with spaced portions in the form of segmental ribs or bars 3, which are preferably located below the top of said support. Certain of said bars are separated from the inner wall 4 of said support each by an open floored passage 5, and it is clearly shown in Fig. 1 that the various passages 25 inter-communicate. Located centrally of said support is a post 6, and positioned substantially at an angle of 180° apart and to extend between the ends 7 of certain of the ribs 3, and spaced apart therefrom, are 30 ribs 8.

The arrows with crossed tails are intended to show the location of a resistance-element when the support 2 is fully "wired", and the arrows without crossed tails show the 40 position of the resistance-element when the said support is only partly "wired".

Intercommunicating with the open passages 5 and the other open floored passages between the ribs or bars 3 and 8 and post 45 6 are passages 9 which communicate with openings or holes 10 formed in the lateral extension 11 of said support. 12 represents in dotted form, terminal posts, which posts project through holes 13 formed in the vertical end of the extension 11. The inner 50 ends of the said terminal posts are located in the holes 10, and are represented as having been smashed or flattened in order that the ends of the resistance-element associated 55 with the support 2 may be attached thereto in any way well-known in the art.

Locating the ribs or bars 3 and 8 and post 6 preferably below the upper surface of the support 2 forms a chamber 14 which 60 will receive the bottom part of a holder 15, which may be in the form of a small pan. This holder is adapted to contain the treating-agent to be transformed.

If desired, the support 2 may be provided 65 with a circular groove or channel 16 of suit-

able size and adapted to be located under the rim 17 of said holder 15 to receive any part of a liquid treating-agent that may overflow from the said holder. However, this groove or channel 16 is not essential 70 and may be omitted.

Obviously when the resistance-element is placed in position, if it be in the form of a wire, it will be covered over by any suitable cement 18. This covering of course 75 will fill in the passages 5 and 9.

It must be clearly understood that the arrows in Fig. 1 are merely illustrative of two ways in which a resistance-element may be associated with the support 2, and it will 80 be obvious that in all cases the ends of the resistance-element will occupy the passages 9, or their equivalent.

19 is a support with which the electric-heating unit already described is associated, 85 and in order to provide for compactness, this support is provided with a chamber 20 conforming to the shape of the sides and bottom of the support 2, and extension 11, and in which chamber said support 2 and its 90 extension are placed. Obviously by grasping the terminal posts 12, the electric-heating unit may be removed and replaced by another one for any desired purpose.

21 is a chamber carried by the support 19, 95 and housing the holder 15. When the treating-agent within said holder is transformed by heat into a vapor or smoke, the same will collect within the chamber 21 and escape therefrom through the outlet 22. 100

In case the transformed treating-agent passing through the outlet 22 be intended to be inhaled, air ports 23 are formed in the support 19 to permit air to pass into the chamber 21 to be mixed with the transformed 105 treating-agent.

In order to prevent lateral displacement of the chamber 21 in respect of the support 19, I form in said support a circular groove or channel 24 which receives the lower edge 110 of the chamber 21. The chamber 21 may be omitted when it is desired to use the device for fumigation purposes.

In the form of the invention shown in Figs. 4 and 5, the support 25 is shown as 115 provided with portions in the form of ribs or bars 26 spaced apart and from bars 27 which surround the said support. 28 are the passages between the ribs or bars 26 and the bars 27, and these passages intercommunicate with passages 29 formed in the neck 30 of said support. Spaced apart from the ribs or bars 26 by the passages 31 are ribs 32 forming an enclosure in which is located a plurality of ribs or bars 33, which 125 latter bars or ribs are spaced apart and from the ribs 32 by the passages 34.

35 are holes formed in the support 25, and these are used to pass the resistance-element therethrough according to the pas- 130

sages between the various ribs or bars referred to it is desired to place a resistance-element in.

The arrows without crossed tails represent 5 the manner in which this form of support is fully "wired," and the arrows with crossed tails represent a manner in which only portion of the said support may be "wired." In the latter case, use is made of passages 36 10 formed in one of the ribs 32.

When the holes 35 are used, the underside of the support 25 may be provided with channels 37 in which to house the resistance-element.

15 In the alternative form just described it is shown that no matter what length the resistance-element may be associated with the support 25, only two terminal posts will be necessary.

20 In the form of the invention shown in Figs. 6 and 7 the support 38 is tubular in form, and mounted within the same is a holder 39 for the treating-agent. This holder must be any suitable incombustible 25 material, such as asbestos, and of course the transformed treating-agent will pass out of the end 40 of said support.

25 41 is a flange associated with the inner end of the support 38, and the opening or passage-way in said support preferably passes through said flange, and it is through the passage-way in said flange that a supply of liquid treating-agent is fed to the holder 39. But as the means for supplying the treating-agent to said holder is not germane to the present disclosures, same is not illustrated.

30 Integrally formed with the support 38 are a plurality of spaced ribs or bars 42 which radiate therefrom, and by following the arrows it will be readily understood how 40 this form of support may be "wired."

35 Formed in the flange 41 are holes 43 adapted to support suitable terminal posts (not shown) to which the ends of the resistance-element will be secured.

40 The ribs or bars 42 may be made in sections as shown at 44 spaced apart longitudinally as shown at 45 to form passages, and without further elaboration it will be 45 clearly understood that the desired length of resistance-element may also be associated with the support 38 in order to secure the desired temperature. It is pointed out that also in this present disclosure under consideration only two binding posts or terminals under all conceivable manners of wiring the support, are necessary.

45 A fixed type of a resistance-element support of the character herein disclosed is universally used in a given field, for "wiring" purposes; that is, the support is common to all units of different "wirings," and is the fixed element in the production of said unit.

50 While I have described what I consider to be the best embodiments within my inven-

tion, it must be understood that the principle thereof may be embodied in many other forms without departing from the spirit of my invention.

Obviously, in the broad combination of 70 the removable resistance-element support, such as 2, having a lateral extension adapted to support terminal posts or their equivalents, with a support or carrying member, such as 19, chambered to receive the first- 75 mentioned support, the first-mentioned support may be formed in any desired manner to hold a resistance-element, consequently it must be clearly understood I am not limited to any particular construction of said first- 80 mentioned support for this purpose.

85 The holder 15 may be omitted, and the treating-agent placed directly in the chamber 14 which may be suitably finished for this purpose.

80 The intercommunicating passages are necessarily formed of major passages, such as 5 and 9 in Fig. 1, and minor passages, such as those between the ends of the ribs 3 and the ribs 8, which latter connect the 90 major passages.

85 As far as I am aware the prior art does not disclose any heating unit, embodying the principle of my invention, provided with two adjacent apertures only through which 95 electrical connections must be made with the ends of the resistance-element. These apertures should be located adjacent each other so that the terminal posts held therein will be spaced the right distance apart to permit 100 the ordinary push plug to be co-operatively associated therewith.

95 The surface of the various disclosures herein which form the bottoms of the passages between the said spaced portions, form 103 floors; and these floors may be imperforate, or perforated in part as disclosed in Fig. 4.

100 While I prefer to use the outlets or openings, such as 10, 29 and 43, in the disclosed embodiments of my invention, in the broadest conception of the idea herein disclosed, I do not confine myself to always using such.

105 What I claim as my invention is:

1. A support for the resistance-element of an electric heater or similar device consisting 115 of a block of suitable material having a plurality of major passages homologously disposed therethrough, and a plurality of minor passages connecting said major passages, whereby resistance-elements of varying lengths may be interchangeably introduced into the block using simultaneously any number of said major and minor passages, and whereby the resistance-element may be placed throughout the block and/or 120 in any given part thereof.

125 2. A support for the resistance-element of an electric heater or similar device consisting of a block of suitable material having a plurality of major passages homologously dis- 130

- posed therethrough; a plurality of minor passages connecting said major passages, and a pair of openings from the exterior of said block, each opening communicating with one of said major passages, whereby resistance-elements of varying lengths may be interchangeably introduced into the block using simultaneously any number of said major and minor passages and whereby the resistance-element may be placed throughout the block and/or in any given part thereof. 3. A support for the resistance element of an electric heater or similar device consisting of a block of suitable material having a plurality of major passages homologously disposed therethrough; a plurality of minor passages connecting pairs of said major passages, and a pair of openings from the exterior of said block, each opening communicating with one of said major passages, whereby resistance elements of varying lengths may be interchangeably introduced into the block using simultaneously any number of said major and minor passages and whereby the resistance element may be placed throughout the block and/or in any given part thereof. 4. As a new article of manufacture, a universal resistance-element support, made of any suitable material, provided with a plurality of spaced segmental ribs, located substantially concentrically; a post located centrally of said support and spaced apart on all sides from the innermost ribs; ribs located substantially at an angle of 180° apart and spaced apart from said other ribs and posts, the spaces between said ribs and posts forming intercommunicating passages, adapted to be selected to form "wiring" passages. 5. As a new article of manufacture, a universal resistance-element support, made of any suitable material, provided with a plurality of spaced segmental ribs, located substantially concentrically; a post located centrally of said support and spaced apart on all sides from the innermost ribs; ribs located substantially at an angle of 180° apart and spaced apart from said other ribs and post, the spaces between said ribs and posts forming intercommunicating passages, adapted to be selected to form "wiring" passages, and a lateral extension carried by said support and provided with passages communicating with the spaces between said ribs, the said passages opening into adjacent holes formed in said extension and adapted to receive binding posts. 6. As a new article of manufacture, a universal resistance-element support, made of any suitable material, and formed with a chamber, a plurality of segmental ribs located substantially concentrically, and in said chamber, said ribs being spaced apart and from the walls of said chamber; a post located centrally of said chamber and spaced apart on all sides from the innermost segmental ribs, and ribs located in said chamber substantially at an angle of 180° apart, and spaced apart from said other ribs and post, the spaces between said ribs and post forming intercommunicating passages adapted to be selected to form individual "wiring" passages. 7. The combination of an integrally formed support adapted to receive a resistance-element, and having a lateral extension adapted for making adjacent electrical connections, and another integrally formed support having a chamber shaped to receive said first-mentioned support and its extension. 8. The combination of an integrally formed support adapted to receive a resistance-element, and having a lateral extension adapted for making adjacent electrical connections, and another integrally formed support having a chamber shaped to receive said first-mentioned support and its extension, and further provided with air ports located outside of said first-mentioned support. 9. In an electric heating device, the combination of a unitary resistance element; a support therefor comprising a block of suitable material having a plurality of major passages disposed therethrough; a multiplicity of minor passages therebetween, and outlets and terminals mounted on said block in said outlets; whereby a resistance element of predetermined capacity may be introduced into a major passage and extended therefrom through and along as many and such major and minor passages as may be adapted to distribute and/or localize the resistance element in any desired area of the device; and adapted to supply thereto that length of resistance element calculated to afford the temperature desired; the said element being connected at its ends to said terminals and constituting a metallic circuit therebetween. 10. In an electric heating device, the combination of a unitary resistance element; a support therefor comprising a block of suitable material having a multiplicity of passages formed therein and intersecting each other at a series of points to provide a multiplicity of selectable paths, and further provided with two outlets; and a terminal mounted in each of said outlets, whereby a resistance element of predetermined capacity may be introduced into said support through and along as many of said passages as may be adapted to distribute and/or localize the resistance element in any desired area of the device, and adapted to supply thereto that length of resistance element calculated to afford the temperature desired; the said element being connected at its ends to said

terminals and constituting a circuit there-between.

11. A support for the resistance element of an electric heater or similar device consisting of a block of suitable material having a plurality of distributed intercommunicating primary and secondary passages whereby a series of selectively combinable passages adapted to afford a range of continuous passages of varying length distributed throughout the block, is provided, whereby a resistance element of given length may be introduced into that selected compounded passage of corresponding length traversing any and/or all sections of the block where heat is to be supplied.
- 10
- 15
12. The method of forming and assem-

bling heating units having a variable range as to distribution and degree of heat, which consists in forming in a block of suitable material a plurality of distributed intercommunicating primary and secondary passages whereby a series of selectively combinable passages adapted to afford a range of continuous passages of varying lengths distributed throughout the block, is provided; placing a resistance element of given length in that compounded passage of corresponding length traversing the whole of the block or any desired section thereof where heat is to be supplied, and leading out the ends of said element for connection to suitable terminals.

EGERTON RYERSON CASE.
